UNITED STATES PATENT OFFICE.

OMER F. CAMPBELL AND FRANK L. PRINDLE, OF CHARLOTTE, MICHIGAN.

RAILROAD-VELOCIPED.

SPECIFICATION forming part of Letters Patent No. 249,895, dated November 22, 1881.

Application filed July 6, 1880. (Model.)

To all whom it may concern:

Be it known that we, OMER F. CAMPBELL and FRANK L. PRINDLE, of the city of Charlotte, in the county of Eaton and State of Michigan, have invented certain Improvements in Railroad-Velocipedes, of which the following is a specification.

Our invention consists in the novel construction and combination of parts, as will be hereinafter described and specifically claimed.

A is the drive-wheel; B B, the foot-cranks attached to the axle of the drive-wheel A, to which the feet of the operator are applied in propelling the velocipede.

C C are the flanged traverse-wheels before and behind the drive-wheel, to keep it in position on the track.

D is the flanged guide-wheel upon the opposite track, keeping the velocipede in an upright position; E, the hinge connecting the guide-wheel to main frame by axle and brace-rod used in folding, as shown in Figure 2.

F is the brace-rod, supporting the velocipede in an upright position, and by which it can be inclined to either side.

H H are the circular bed-pieces, receiving the axle of the drive-wheel A and traverse-wheels C C, being firmly bolted together at the

point of intersection with circular back, and also by means of shouldered stationary axles, 30 upon which the traverse-wheels revolve.

I is the circular back, supporting seat and brace-rod F. The standards J J are firmly bolted to the back I and bed-pieces H H.

K K are the rods by which the frame and 35 wheels are adjusted to the track.

L is the seat for the operator of the velocipede.

In folding the guide-wheel the rod M is taken from its fastening at N and the guide-wheel swung back on the catch N, and the rod M dropped into the hook on end of handle O, as shown in Fig. 2.

The mode of operating a velocipede of this class is well known to those skilled in the art— 45 hence, need not be repeated herein.

We claim as our invention—

In a railroad-velocipede, the semicircular bed-pieces H H, for supporting and maintaining the wheel A, C, and D in vertical and horizontal positions, as shown and described.

OMER F. CAMPBELL.
FRANK L. PRINDLE.
